[57] CLAIM

The ornamental design for a computer hard drive tray, as shown and described.

DESCRIPTION

FIG. 1 is a perspective view of a computer hard drive tray having features in accordance with the present invention, the bottom support, rear wall, side walls, and slide rails being shown in phantom for illustrative purposes only and forms no part of the claimed design;

FIG. 2 is a front elevational view of the computer hard drive tray of FIG. 1;

FIG. 3 is a top plan view of the computer hard drive tray of FIG. 1;

FIG. 4 is a bottom plan view of the computer hard drive tray of FIG. 1;

FIG. 5 is a right side elevational view of the computer hard drive tray of FIG. 1; and,

FIG. 6 is a left side elevational view of the computer hard drive tray of FIG. 1.

The broken line disclosure in FIGS. 3-6 is for illustrative purposes only and forms no part of the claimed design.
